(57) **CLAIM**

The ornamental design for a golf glove, as shown and described.

DESCRIPTION

FIG. 1 is a perspective view of the back portion of the golf glove.

FIG. 2 is a perspective view of the back portion of the golf glove; and,

FIG. 3 is a perspective view of the thumb side of the golf glove.

The broken lines of FIGS. 1-3 showing the glove body and finger casings are for illustrative purposes only and form no part of the claimed design.

1 Claim, 2 Drawing Sheets

FIG. 1

FIG. 2
